[57] CLAIM

The ornamental design for a portable computer, as shown and described.

DESCRIPTION

FIG. 1 is a top, rear, right side perspective view for a portable computer showing my new design, with the lid being closed and the handle in its extended position;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a front elevational view thereof;

FIG. 8 is a right side perspective view thereof in an opened position, with the handle serving as a support;

FIG. 9 is a right side elevational view thereof;

FIG. 10 is a left side elevational view thereof;

FIG. 11 is a top plan view thereof with the keyboard and display being exposed;

FIG. 12 is a front elevational view thereof;

FIG. 13 is a rear elevational view thereof;

FIG. 14 is a bottom plan view thereof;

FIG. 15 is a top, rear, right side perspective view of a second embodiment of my new design, with the lid being closed and the handle in its extended position;

FIGS. 16 and 17 are respectively right and left side elevational view thereof;

FIG. 18 is a rear elevational view thereof;

FIG. 19 is a top plan view thereof;

FIG. 20 is a bottom plan view thereof;

FIG. 21 is a front elevational view thereof;

FIG. 22 is a right side perspective view thereof, in an opened position, with the handle serving as a support;

FIGS. 23 and 24 are respectively right and left side elevational views therewith the lid in an opened position;

FIG. 25 is a top plan view thereof, keyboard and display being exposed;

FIG. 26 is a front elevational view thereof;

FIG. 27 is a rear elevational view thereof;

FIG. 28 is a bottom plan view thereof.
